UNITED STATES PATENT OFFICE.

JOHN A. HAGERSTROM, OF CRANFORD, NEW JERSEY.

COVER GRIP.

Application filed April 17, 1922. Serial No. 554,239.

To all whom it may concern:

Be it known that I, JOHN A. HAGERSTROM, a resident of Cranford, in the county of Union and State of New Jersey, have invented certain new and useful Improvements in Cover Grips, of which the following is a specification.

This invention relates to lifters for lids and it more especially appertains to a manipulating appendage for covers and the like, made of different material from the latter.

The main object of the invention is to provide an article of the character described, capable of being molded into or embraced by the seal of a container, and also used as a means for removing and replacing the same.

Another object is to produce an article of the nature set forth, particularly adaptable for use as a finger grip in conjunction with a paraffin closure over a glass of jelly, not only without interfering with the primary sealing function thereof, but enabling also this seal, after it has once been opened, to be utilized as a lid for the glass.

A further object is the production of an article of the type specified, which after the paraffin lid associated therewith has served its purpose can be separated from it, and again applied to another covering seal, for further service.

Still another object is the provision in an article of the class mentioned, of means combined therewith for holding a label or other device, whereon may be denoted the contents of the receptacle with which the same cooperates.

A still further object is to furnish a practical article of the kind referred to, composed of few, simple parts, light but strong and durable, readily applied or removed, convenient to handle, safe and sanitary to use, besides amenable to low cost of manufacture.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawing, wherein like parts are designated by the same refer-

ence characters throughout the several views.

The usual way of removing a paraffin cover seal from the top of a jelly jar, glass or receptacles for other preserves, is to press down with a thin bladed knife where the paraffin adheres to the walls of the container, all around the latter, and then try to pry up the seal cover. This procedure not only frequently cracks or breaks up the seal in pieces, making the same unfit for further use, but very often a thin ledge or crust of the paraffin becomes stuck to the glass or jar. In view of the loathsome appearance of these remnants, an attempt is made usually to dislodge the same. However, the general outcome of such efforts is, that the loosened pieces of the paraffin fall into the jelly and must be scooped out with a spoon, when in order to remove all of the fragments it is unavoidable to simultaneously take up appreciable quantities and even as much as a whole layer of the jelly. Obviously this occasions loss of time and patience beside waste of the receptacle's contents. Moreover, recourse must be had to another cover for the jelly glass, and it is a common occurrence to see a small dish, such as a saucer, employed for the purpose. But as this combination hardly enhances the aesthetic appearance of a well-set table, the jelly container with its makeshift cover, is ordinarily brought in only as wanted and then carried out at each meal. The several disadvantages above discussed resulting from the old fashioned method of opening up and removing a paraffin seal cover of the class referred to, as also from the subsequent handling thereof, are overcome by the present invention.

Generally described, the article under consideration includes in its organization a carrying or base member designed for superimposition upon or over the matter to be protected by a sealing substance, and adapted to be molded into or under the latter. From this member extends up an element constituting a manipulating grip for, and located at a higher level than the member and the thereby carried sealing substance. The seal-carrying article when once removed from the matter which it protects, affords a replaceable cover for the container thereof, while the member coacting with the cover provides a reinforcement therefor. Means combined with the article are capable of

receiving a label device denoting the nature of the matter in the container. The inter-relative arrangement of the cooperating sealing substance and carrying member 5 therefor, is preferably such that these parts can be separated one from another for further use.

The advantages of the invention as here outlined are best realized when all of its 10 features and instrumentalities are combined in the one and same structure, but, useful devices may be produced embodying less than the whole.

It will be obvious to those skilled in the 15 art to which the invention appertains, upon becoming conversant with the details thereof, that the same may be incorporated in several different constructions. The accompanying drawing, therefore, is submitted 20 merely as showing the preferred exemplifications of the invention.

In the said drawing:—

Figure I is a top plan view of a jelly glass with its sealing cover, showing one type 25 of the present article applied thereto;

Fig. II is a central section taken vertically thru the parts illustrated by the preceding figure, a portion thereof being broken away;

Fig. III is a detached top plan view of the 30 preferred form of the invention;

Fig. IV is a vertical section taken centrally thru the last named figure, and further shows in dot-and-dash lines a label device carried by the said article;

Fig. V is an end view of the same form 35 of the invention looking from the right hand side of the two latter views;

Fig. VI is a detached top plan view of a modified form of the invention;

Fig. VII is a central longitudinal section 40 of the form of the invention shown by Fig. VI, looking up from the lower edge of the latter; and

Fig. VIII is a perspective view of another modification of the present invention, 45 also showing the lower portion of the said device.

Referring now to these views for a detailed description of the invention exemplified, the known parts of a container and its seal wherewith this lifter coats, have been designated by reference letters instead of numerals, as used to denote the present improvements, since the said parts are not 55 claimed as pertaining to the latter, except in so far as they may form therewith legitimate combinations of elements capable of yielding novel and useful results.

Of these reference letters, "A" denotes a 60 container which may be a glass jar or other receptacle suitable for holding jelly or other substances as at B, and adapted to be covered by a sealing material C. Prior to depositing the latter, which may be composed of paraffin, wax or like materials

capable of being molded, or immediately after a thin layer of the same has been poured upon the contents B in the receptacle A, the improved grip or lifter is positioned approximately in the middle thereover. 70

As will be noticed from all of the views on the accompanying drawing, the cover lifter forming the subject matter hereof, includes a base or carrying member, which in its simplest form, shown in Figs. I and II, 75 is designated by the numeral 11, and may be of circular or any other desired outline. Extending up approximately from the centre of this member, is a manipulating element or knob 13 wherewith the lifter in 80 its entirety can be handled. The said grip element may be included within a substantially semi-circular portion 15 produced by slitting the base 11 and leaving a similarly shaped opening therein. The ear thus forming the element 18, is then bent upwardly from opposite points 16, 17, where the slit terminates, which points are located on a line passing diametrically thru the base member. As indicated at 19, a hole 85 may be provided in the ear knob 13, in order to enhance the facility of gripping the same.

After the jelly in the glass has congealed, the base of the lifter is placed on it and molten paraffin is poured thereover, covering the same and the jelly's top surface for a depth of about an eighth of an inch or so. It will be understood, that the fused paraffin, wax or other sealing material employed, 95 flows thru the opening in the member left 100 by the ear 13, and all around the base of the latter in such a way as to firmly anchor the lifter in the seal proper, and at the same time serve to exclude the air from the jelly, 105 in the usual manner. When it is desired to reach the contents of the glass or jar for the first time, subsequent to the hardening of the paraffin, it is an easy matter to press around the edges of the covering seal so as 110 to loosen it from the inside walls of the container. Then by gripping the upstanding ear 13 between the fingers and lifting thereon, the conjoined paraffin seal and base 11 115 which acts as a carrier therefor, will readily come off or out of the glass. Upon removal of the required quantity of jelly or preserves from the container glass, the covering seal can be replaced as often as wanted. By merely putting the cover seals with the 120 molded-in lifters into hot water, or otherwise heating them, the cover lifters are quickly detached and can be saved or reclaimed so as to enable them to be used over and over again for several seasons.

In the preferred embodiment of the invention represented by Figs. III to V, as well as in the remaining views of the annexed drawing, the parts substantially the equivalent of those already described, are 125 designated by the same reference characters 130

to which letter exponents are suffixed. Thus 11^a is the base member, 13^a the ear element, and 15^a the slotted opening in the base providing the latter. Besides the aforementioned opening 15^a, another slit 21 is formed in the member 11^a but in opposed offset relation to the former. As will be noted, the latter named slit 21 is of smaller size and consequently the supplemental ear 22 produced thereby is also of less dimension than the central, main or gripping ear 13^a. When the smaller ear 22 is bent up parallel to the companion element 13^a, the former is made to stand a short distance 15 away from the latter so that a gap 23 is left therebetween. This gap provides a receiver or holder for a card or other label device D. An appropriate description pertaining to the nature and contents of the receptacle can 20 conveniently be denoted on the card entered into the said holder gap 23. The paraffin that is molded around the base member, will also serve to anchor the label D in its assigned position. It is obvious that such a 25 label can also be inserted, if so desired into the hole 19 of the ear 13 shown by Fig. II.

With the object of making the manipulating grip less liable to slip between the fingers of the person handling it, the same may 30 be provided with bead-like protuberances 25 struck up on both sides of the said element 13^a. The two types of lifters previously disclosed may conveniently be punched from thin plate aluminum, or other sheet metal 35 that is given a protective coating of tin, either of which is sanitary and not appreciably affected by preservatives in general. However, to make them absolutely hygienic, the base member and part of the grip element can be dipped in melted paraffin and 40 then cooled off, prior to placing the lifters on top of the edibles stored in the receptacles therefor. It will be observed that as shown at 26 the lower edges of the ear 13^a are undercut, in order to enable them to 45 more readily leave the sides of the opening 15^a during the bending operation.

Referring to the construction depicted by Figs. VI and VII, the former view illustrates the base member 11^b and ear element 13^b of the lifter as lying down flatwise in one plane, prior to the element being bent upwardly from the slit 15^b, that severs it from the said member. As will be noticed, the ends of this slit are continued beyond a line 27 upon which the ear 13^b is folded to an erect posture and form horns or retainers 29, 30, one on each edge of the said ear. These retainers are provided with inwardly 55 facing lips or abutments 31, 32, respectively, which are designed to take around the far side of the upstanding ear, with regard to their location relatively to the latter, as will be seen to best advantage in Fig. VII. 60 The arrangement just described, is especially

adaptable when the lifter is made of paper, which incidentally should be tough and strong, preferably of a variety reinforced by fabric. The retainers with their abutments coact to prevent the ear grip 70 from springing back, particularly at such times as the hot paraffin is poured around the same. In connection with this type of lifter, it is apparent, that as it is made of paper, the inscription pertaining to the 75 species of the goods to which the same is applied, can be made directly thereon, whereby a separate label is dispensed with.

In the modified form of the invention represented by Fig. VIII, the lifter is shown as consisting of a piece of wire or strip material, bent to include a base member in the horizontal plane, and an ear element substantially perpendicular thereto. The base member comprises the end portions 11^c and 11^d of the wire, which are oppositely disposed and as shown, can be of open hook formation. The ear or grip element rises from the intermediate part of the wire, and is wound to form practically a pair of convolutions 13^c and 13^d, which may be spaced or forced apart to receive between them a card or label D¹.

Altho this device has been described as relating principally to means for lifting seal-covers of containers, it is obvious that the same can equally as well be used to dislodge such or similar closures, by forcing the latter downwardly instead, if properly anchored thereto, and the circumstances admit thereof.

While certain preferred embodiments of this device have been shown and described, it will be understood that changes in the form, arrangements, proportions, sizes and details thereof may be made, without departing from the scope of the invention as defined by the appended claims.

Having described my invention what I desire to secure by Letters Patent and claim, is:—

1. An article of the character described comprising in combination with a container and the covering-seal therefor, a base member arranged to reinforce the seal, and an element constituting a grip for the latter extending from said member.

2. An article of the character described comprising in combination with a container and the covering-seal therefor, a member adapted to be molded into the seal serving as a carrier therefor, and a grip element for the latter extending up therefrom thru the seal.

3. An article of the character described comprising in combination with a container and the covering-seal therefor, a member capable of carrying the latter held therein, and an element formed from said member constituting a grip therefor and the con-

joined seal, said element leaving an opening in the member adapted to receive the sealing material.

4. An article of the character described comprising in combination with a container and the covering-seal therefor, a member embraced by the material constituting the seal, an element arising from said member forming therewith a seal-lifter, and means included in the latter adapted to receive a sign bearing device.

5. An article of the character described comprising in combination with a container and the covering-seal therefor, a disc shaped member adapted to be embedded in the sealing substance, an ear like element slitted from said member, being bent up at substantially right angles thereto, and anti-slipping means formed with said element.

6. An article of the character described comprising in combination with a container and the covering-seal therefor, a member adapted to be grasped for the major part thereof by the sealing substance, an element

constituting a grip for the conjoined member and seal, and a supplementary element coacting with said grip element to provide a label holder.

7. An article of the character described comprising in combination with a container and the covering-seal therefor, a reinforcing member for the seal, and elements extending in spaced relation from said member forming between them a label holder, one of said elements serving as a grip for the conjoined member and seal.

8. An article of the character described comprising in combination with a container and the covering-seal therefor, a member adapted to be surrounded by the substance forming the seal, an element rising from said member constituting a grip therefor and the thereby carried seal, and projections provided near the upper portion of said element serving to increase the gripping surface thereof.

JOHN A. HAGERSTROM.
